UNITED STATES PATENT OFFICE.

FRANK D. WARD, OF NEW YORK, N. Y., ASSIGNOR TO FRANK D. WARD AUTOMATIC MACHINE CORPORATION, OF NEW YORK, N. Y., A CORPORATION OF NEW YORK.

MACHINE FOR ROLLING RINGS.

1,200,401.

Specification of Letters Patent.

Patented Oct. 3, 1916.

Application filed February 26, 1916. Serial No. 80,609.

To all whom it may concern:

Be it known that I, FRANK D. WARD, a citizen of the United States, and a resident of the city, county, and State of New York, 5 (whose post-office address is 17 Battery Place, New York city,) have made a new and useful Improvement in Machines for Rolling Rings, of which the following is a description in such full, clear, and exact 10 terms as will enable any person skilled in the art to which it pertains to make and use the same.

According to my invention a ring of cast or otherwise formed ductile or malleable 15 metal is subjected to an operation which simultaneously compresses or compacts the metal of the ring and elongates or draws out the metal, thereby enlarging the ring and producing a product which is very 20 tough, compact and even in its texture. These rings are useful in numerous situations notably as packing rings for projectiles.

Referring to the accompanying drawings: 25 Figure 1 is a side elevation of the machine; Fig. 2 is a plan view of the same; Fig. 3 is a right hand end elevation (referring to Fig. 2.); Figs. 4 and 5 are elevational views of the rocking frame and its operating lever; 30 Fig. 6 is a cross-sectional elevation of the machine showing the forming rolls and the work guide; and Fig. 7 is an enlarged elevation with parts broken away showing the forming rolls and their mounting devices together with the work ring or work piece.

The work ring (indicated by the letter *a* in Fig. 7) is acted on by and between two rolls 10 and 11, the latter having side flanges 12 between which the former roll enters. The precise shape of the rolls varies of course, with the form of the work being produced and one of the rolls is arranged to move laterally of its axis to and from the other roll to permit the introduction and removal of the work after which the laterally or transversely movable roll is drawn back into active position and both of the rolls are then rotated with the work ring between them. The result of this operation is that the metal of the ring is drawn down or elongated and the ring simultaneously enlarged. This results in toughening or compacting the texture of the copper or other metal and a corresponding enlargement of the ring circumferentially.

The rolls 10 and 11 are carried on stub-shafts 14 and 15 which are tapered into the ends of heavy journals 16 by which the stub-shafts and drawing rolls are mounted. The stub-shafts are rigidly held in the journals 60 16 by tie-bolts 17 extending axially through the journals and furnished with nuts or other fastenings on the outer ends thereof. The right hand journal 16 is rotatably mounted in bearings 18 in the frame of the 65 machine and its axial position is adjustably maintained by a guide 19 running in annular groove 20 in the journal between the bearings 18. This guide plate 19 is held rigidly yet adjustably between the bearings 70 18 or boxes 18 by means of a screw shaft 21 fitted in the frame and furnished with suitable lock nuts and the like for holding the guide 19 securely in its position transverse of the journal and within the groove 20 to which position the guide plate may have been previously and purposely adjusted, without however permitting any axial motion after the guide plate has been adjusted and fastened. The outer end of the right hand journal 16 has fixed to it a spur gear 22 which meshes with the pinion 23 on a rotary shaft 24 mounted in the frame and adapted to be driven in any desired manner from a motor or any other source of power.

The second or left hand journal 16 is rotatably mounted in boxes 25 formed in a secondary frame 26. The secondary frame extends transversely of the main frame and is mounted to rock around a shaft 27 carried longitudinally in the main frame parallel with the shaft 24. The boxes 25 are furnished with a guide plate 19 and adjusting screw 21 the same as before described which coöperate with the left hand journal 16 also as before described. The left hand journal 16 carries a spur gear 28 which is in mesh with a pinion 29 fastened to the shaft 27. The shaft 27 is journaled in the main frame and extends to the right hand end of the machine where it is furnished with a pinion 28¹ in mesh with the spur gear 29¹ on the shaft 24. Thereby the shafts 24 and 27 are caused to rotate in unison and in such a manner that the two journals 16 are driven in opposite directions notwithstanding that the secondary frame 26 may be simultaneously swinging around the center of the shaft 27.

The secondary frame 26 has a counter-weight 30 at its rear end and its forward end is articulated to a toggle 31. The toggle at the pivot between its links is joined 5 to a link 32 and this link 32 in turn is joined to a hand lever or operating arm 33 which has a shoulder 33^a adapted to fall down in front of a locking wall 34 on the frame thereby holding the parts securely in working 10 position until the arm 33 is purposely *i. e.* by manual operation, lifted. The arm 33, engaging the locking wall or shoulder 34 as shown in Fig. 4, prevents the toggle 31 from breaking into the position shown 15 in Fig. 5 unless the arm 33 is lifted clear of the shoulder 34 and this lifting must be done manually and cannot be done accidentally. This lifting of the arm 33 results in thrusting backward the link 32 and breaking 20 the toggle 31 which results in swinging down the front end of the secondary frame 26 and moving the roll 11 transversely of its axis away from the roll 10 so as to allow the introduction and removal of the work. 25 It will be further noted that the arm 33 is articulated by a link 34^a (see Figs. 4 and 5) to the locking wall or shoulder 34 which constrains or confines the movement of the arm and further forms with the arm a second toggle operating with the first toggle formed by the links 31. Therefore the frame 26 is controlled by two toggles, *i. e.* a main toggle 31 and an operating toggle composed of the links 32 and 34^a which latter or operating toggle is thrown back and forth by the hand lever 33.

On the main frame of the machine at the station occupied by the rolls 10 and 11 is a work gage comprising a stationary part 35 40 furnished with lugs 36 to attach it to the frame and a swinging or opening part 37 connected to the part 35 at its bottom by hinge 38 and having a lug 39 at its top loosely received in a guide 35^a on the section 35.

40 is a hand cam to lock the lug 39 and the section 37 rigid with the section 35, but which when released allows the section 37 to drop back slightly for the introduction 50 and removal of the work. The gage 35—37 embraces the rolls 10 and 11 as shown but the part of the guide which embraces the roll 11 is much larger than the roll and is in fact of an internal diameter (when the cam 40 is locked) equal to the designed external diameter of the work ring when finished. Therefore in the operation of the machine when the work is in place between the rolls 10 and 11 the rolls are operated to draw and enlarge the ring and this operation is continued until the ring is enlarged to the internal diameter of the work gage 35—37 when the same is closed. When the ring is thus enlarged the operation is completed, the rotation of the dies may or may

not be stopped, the guide segment 37 is allowed to fall back and the arm 33 is thrown up which separates the rolls 10 and 11 and the finished ring may be readily removed. A new ring is then inserted; the guide segment 37 is moved back, the cam 40 locked and the arm 33 is thrown down to restore the toggle 31 and return the rolls 10 and 11 to operation. 70

The process and product described herein 75 is made the subject of the claims in my co-pending application, filed June 22, 1915, Serial No. 35526 entitled "Process and product of making rings."

Having thus described my invention, 80 what I claim as new and desire to secure by Letters Patent of the United States is:—

1. In a machine for rolling rings, the combination of opposing rollers adapted to roll the ring between them to extend the 85 ring and a continuous curved work gage encircling the ring and serving to limit the extension thereof.

2. In a machine for rolling rings, the combination of opposing rollers adapted to 90 roll the ring between them to extend the ring and a continuous curved work gage encircling the ring and serving to limit the extension thereof, said work gage having a movable part which may be thrown back to 95 release the work.

3. In a machine for rolling rings, the combination of opposing rollers adapted to roll the ring between them to extend the ring and a continuous curved work gage encircling the ring and serving to limit the extension thereof, said work gage having a section adapted to drop away or move laterally from the work to release the same. 100

4. In a machine for rolling rings, the 105 combination of opposing rollers adapted to roll the ring between them to extend the ring and a continuous work gage encircling the ring and serving to limit the extension thereof, said work gage having a section 110 adapted to move to and from the work for the purpose specified and a cam latch to releasably hold the movable section in place.

5. In a machine for rolling rings the combination of opposing rolls adapted to roll the ring between them, both rolls mounted on driven shafts which extend in opposite directions respectively from the rolls and means for carrying one shaft to move laterally bodily toward and from the other 120 whereby the rolls may be squarely engaged and disengaged.

6. In a machine for rolling rings the combination of opposing rolls adapted to roll the ring between them, both rolls mounted 125 on driven shafts which extend in opposite directions respectively from the rolls, means for carrying one shaft to move laterally bodily toward and from the other whereby the rolls may be squarely engaged and dis- 130

engaged and means for driving one of the shafts at a higher speed than the other.

7. In a machine for rolling rings, the combination of a rotary shaft, a fixed bearing for said shaft, a rocking frame, means for rocking it, a second rotary shaft carried in the rocking frame so that the second shaft has a planetary motion around the first shaft, means for rotating the shafts irrespective of the said planetary motion and rollers mounted on the shafts to roll the ring between them.

8. In a machine for rolling rings the combination of opposing rolls to roll the ring between them, a rotary shaft mounted in fixed bearings carrying one roller, a rocking frame, a rotary shaft mounted therein and carrying the other roller, a toggle con-

necting the rocking frame with a stationary part of the machine and a hand lever including a second toggle for making and breaking the first toggle.

9. In a rolling machine or mill the combination with the opposing rolls, of tapered arbors to carry them, shafts with recessed ends in which the arbors are fitted and screws mounted longitudinally in the shafts and engaging the arbors removably to hold them in place.

In testimony whereof I have hereunto signed my name in the presence of two witnesses.

FRANK D. WARD.
